UNITED STATES PATENT OFFICE

101,990

DESIGN FOR A RADIATOR ORNAMENT

Franklin Q. Hershey, Detroit, Mich., assignor to
General Motors Corporation, Detroit, Mich., a
corporation of Delaware

Application October 5, 1936, Serial No. 65,161

Term of patent 3½ years

To all whom it may concern:

Be it known that I, Franklin Q. Hershey, a citizen of the United States and resident of Detroit, county of Wayne, and State of Michigan, have invented a new, original, and ornamental Design for a Radiator Ornament, of which the following is a specification, reference being made to the accompanying drawing, forming a part thereof.

Figure 1 is a side elevation of the radiator ornament showing my new design.

Figure 2 is a plan view.

Figure 3 is a front elevational view.

I claim:

The ornamental design for a radiator ornament, as shown.

FRANKLIN Q. HERSHY.
